DAM AND METHOD OF CONSTRUCTING THE SAME

Filed March 15, 1928

UNITED STATES PATENT OFFICE

FRED A. NOETZLI, OF LOS ANGELES, CALIFORNIA

DAM AND METHOD OF CONSTRUCTING THE SAME

Application filed March 15, 1928. Serial No. 261,979.

This invention relates to the construction of concrete and masonry dams of the arched type and the primary object of the invention is to provide a dam of this type which will be

5 less expensive and which can be built in a shorter period of time than dams such as heretofore constructed.

Under the pressure of the water an arched dam is deflected in a down-stream direction.

10 This deflection involves generally large bending moments in the horizontal arches as well as in the vertical cantilevers. The thicker and therefore the stiffer these arches and cantilevers are relative to the span and height,

15 the greater are in general the bending moments and the corresponding stresses.

In Fig. 3 of the Patent No. 1,410,217 granted to me March 21, 1922, a joint is shown in an arch dam which has a similar function as 20 the corresponding device described in the present specification and in the appending claims. However, the joint shown in Fig. 3 of the Patent No. 1,410,217 is located in the lower portions of the dam only and has the 25 definite function of reducing the cantilever stresses near the base of the dam. It will be observed, however, that any movement of the portions of the dam on opposite sides of the joint will tend to produce heavy shearing 30 stresses at the upper end of the joint which necessitates the placing of steel reinforcement in the dam in this region in order to prevent the concrete from cracking.

In my improved dam the joint extends upward to the down-stream face of the dam which makes steel reinforcement along the upper end of the joint generally unnecessary. This arrangement permits also of an unfailing 35 draining of the joint and has other advantages as pointed out subsequently.

The objects of my invention are, first, to build a dam of the arched type in which the arches and cantilevers are made more flexible than they would ordinarily be by dividing 40 them into a plurality of laminæ separated by joints; second, to extend these joints from the base of the laminæ to the top of the dam or at least to the intersection with the down-stream face; third, to provide a water-proofing 45 membrane in one or more of the joints:

and fourth, to build the dam in steps by raising the individual laminæ alternately. Other objects of my invention will be pointed out subsequently.

In the accompanying drawings in which 55 my improved dam is illustrated.

Figure 1 is an elevation of the dam;

Figure 2 is a typical vertical section through the dam;

Figure 3 is a typical horizontal section 60 through the dam;

Figure 4 is a typical section through the center of the dam.

Referring to Figure 1: The dam shown comprises an arch A spanning between the 65 abutments B. The arch A comprises two arch laminæ, an up-stream arch 1 and a down-stream arch 2. There is a continuous joint 3 between the arches 1 and 2.

Figure 2 is a vertical section along the line 70 2-2 of Fig. 1. The joint 3 is shown to extend from the bottom of the two arches 1 and 2 upward to the intersection with the down-stream face of the dam. For the purpose of

analysis and to facilitate describing the structural behaviour of an arch dam, such a structure is usually assumed as consisting of a series of elementary horizontal arches and a series of vertical cantilevers. Figure 2 illustrates the vertical cantilever laminæ C and 75 D of the dam, and it is of importance to note that the joint 3 separates not only the two arches 1 and 2 but at the same time the two vertical cantilever laminæ C and D.

It is of advantage to make the down-stream cantilever lamina D somewhat thicker than the up-stream lamina C in the vicinity of the base of the dam, in order to make the down-stream lamina D relatively stiffer in a vertical direction than the up-stream lamina C. 80 In Fig. 2 are also shown the axes 4 and 5 of the two cantilever laminæ C and D. These axes form an acute angle with each other.

Figure 3 is a typical horizontal section 85 along the lines 3-3 of Fig. 1. The two arch laminæ 1 and 2 are shown separated by the joint 3 which extends substantially from abutment to abutment of the arch A. In case that the arch A is of a uniform thick- 90 100

ness in horizontal planes the joint 3 is preferably placed approximately concentric with the surfaces of the arch A. In case that the arch A is thicker at the abutments than at the crown, for instance, as shown by Fig. 3, the up-stream arch 1 is preferably also thicker at the abutments than at the crown. There are vertical radial joints 6 in the up-stream arch 1, and similar joints 7 in the down-stream arch 2. The joints 6 are preferably off-set laterally with regard to the joints 7.

One of the main objects of the joint 3 is to make the horizontal and vertical elements of the dam more flexible. This has the effect of decreasing the rib-shortening and temperature stresses in the arches. The flexibility of the vertical cantilever laminæ is also greatly increased by the joint 3. Thus, for a certain load on a vertical element of the dam the deflection is increased approximately four times by the use of a joint 3 over that of the same vertical element having no joint. Thus, a larger percentage of the water load is supported by the much more economical arch action, and the stresses in the vertical elements are greatly reduced. In Fig. 3 are further shown reinforcing steel bars 8 crossing the plane of the joint 3. These bars 8 will tend to equalize the stresses at the junction of the two laminæ and prevent cracking of the concrete.

When the arches 1 and 2 deflect under the water load, the up-stream arch 1 will have compression at a point X at the intrados near the abutments. The down-stream arch 2 will have much less compression, and possibly tension at the point Y opposite point X at the extrados of the down-stream arch 2. Consequently there will be the tendency of a movement in opposite directions of the point X relative to the point Y. In order to permit such a movement which is an essential feature of my improved dam, the friction in the joint 3 must be as small as practicable. In my improved dam the joint 3 is specially prepared for such a purpose by smoothing the surface of the concrete, or by painting the same with asphalt or other suitable substances. I may also provide a waterproofing membrane applied to the extrados of the down-stream arch 2. Besides lubricating the joint 3 this membrane will have the most desirable effect of preventing any water from percolating from the reservoir to the down-stream face of the dam. All water percolating to the joint 3 may be drained by means of special drain pipes 9 and carried through a tunnel 10 or other drains 11 to the down-stream side of the dam. Water seeping into the joint 3 would do no damage even if permitted to rise to the crest of the down-stream arch 2 where it could be drained off by pipes 12 as shown in Fig. 1. Otherwise it would flow away by itself and thus prevent the down-stream arch 2 of ever hav-

ing to support more direct water pressure than with water to its top.

The horizontal arch laminæ and vertical cantilever laminæ of my improved dam have an area of substantially loose contact between two adjoining laminæ, and the extrados of the down-stream arch 2 is substantially in contact with the intrados of the up-stream arch 1, except for the waterproofing or other material in the joint 3.

Figure 4 is a vertical section along the line 4—4 of Fig. 1. In Fig. 4 are shown a plurality of cantilever laminæ C and D with joints 3.

In constructing my improved dam I may build first the down-stream arch 2 to a certain height, then I prepare the extrados of arch 2 in a suitable manner so as to prevent adhesion of concrete to said extrados. Then I build the up-stream arch 1 by pouring the concrete against the extrados of the down-stream arch 2.

Before building the up-stream arch I may first waterproof the extrados of the down-stream arch 2. I may also place drain pipes 9 approximately in the plane of the joint 3 and provide an outlet tunnel 10 or a drain pipe 11 leading to the down-stream face of the dam.

I use suitable construction methods for building a plurality of arch laminæ 1 and 2, with joints 3 between said laminæ for the purpose of enabling a relative movement taking place between each two adjacent laminæ.

Thus, I may construct my improved dam by placing and holding in place during concreting a continuous sheet of elastite, tar paper, asphalted burlap or other suitable material for a waterproofing or lubricant in the proper position and then pouring concrete on both sides of said sheet. This sheet will prevent bonding of the concrete and thus form a joint 3 parallel and between the arch laminæ 1 and 2 of my improved dam.

In some cases the joint 3 will start at the base of the dam; in other cases it may start higher up.

I claim:

1. An arch dam comprising a plurality of arch laminæ, and an area of substantially loose contact between two adjoining said laminæ, said area extending upward from the bottom of said laminæ to the down-stream face of said dam.

2. In an arched dam between abutments the combination of an up-stream arch and a down-stream arch, the extrados of the down-stream arch being in contact with the intrados of the up-stream arch, said arches being otherwise independent of each other except near said abutments.

3. In an arched dam as described in claim 2, the additional provision of a lubricant between said arches tending to facilitate the

movement of said arches relatively to each other.

4. In an arched dam as described in claim 2, the additional provision of drains for carrying away any excess water that might tend to accumulate between said arches.

5. In an arched dam as described in claim 2, the extrados of said down-stream arch being provided with a water-proofing mate-¹⁰rial.

6. In an arched dam supporting water pressure, the combination of a plurality of cantilever laminæ, two of said cantilever laminæ being separated by a joint of curved ¹⁵contour extending substantially from the bottom of said laminæ upward to the down-stream face of said dam, a water-proofing material in said joint, and suitable means for disposing of excess waters that may tend to ²⁰accumulate in said joint.

7. In a concrete arched dam stressed by water pressure the combination of an up-stream arch lamina and a down-stream arch lamina supported by abutments, with a joint ²⁵between said laminæ, said joint extending from the base of said laminæ upwards to the down-stream face of the dam, a lubricating material in said joint for facilitating a relative movement of certain portions of ³⁰said arch laminæ with regard to each other in such a manner that the concrete near said abutments is stressed relatively more near the intrados of said up-stream lamina than near the extrados of said down-stream lamina ³⁵when the water pressure on the dam is increased.

8. In an arched concrete dam the combination of two laminated vertical cantilevers with a joint between said cantilevers extending ⁴⁰from the base of said cantilevers upward to the intersection with the down-stream face of said dam, suitable means for reducing the friction in said joint such as to increase the flexibility of said dam in a vertical direc-⁴⁵tion.

9. An arch dam between abutments, said dam comprising two arch laminæ and a joint between said laminæ extending between said abutments, and reinforcing bars extending ⁵⁰across the plane of said joint so as to confine the extension of said joint between such limits as may be desired.

10. In an arched dam the combination of an up-stream and a down-stream arch lamina, ⁵⁵with substantially radial joints in said laminæ, said joints in said down-stream lamina being disposed laterally relative to the said joints in said up-stream lamina.

11. In a dam an arch between two abut-⁶⁰ments, a joint dividing said arch into an up-stream arch and a down-stream arch, the up-stream arch being thicker near the abutments than near the crown of said arch.

12. In an arched dam the combination of ⁶⁵an up-stream and a down-stream cantilever

lamina separated by a joint, said down-stream lamina in the vicinity of the base of said dam being thicker than said up-stream lamina.

13. In an arched dam the combination of two cantilever laminæ with a joint between said laminæ, said joint extending from the base of said laminæ upward to the down-stream face of said dam, the axes of said cantilever laminæ forming an acute angle ⁷⁰with each other.

14. The method of constructing a concrete arch dam comprising an upstream and a downstream arch with a joint between said arches, by building said dam to a certain height, then placing a sheet of material ex-⁸⁰tending upwardly in the direction of said joint, and then pouring concrete substantially simultaneously on both sides of said sheet.

15. The method of constructing a concrete arched dam comprising an upstream and a downstream arch with a joint between said arches, by building said dam to a certain height, then placing a sheet of material ex-⁸⁵tending upwardly in the direction of said joint and providing drainage means along-⁹⁰side of said sheet, and then pouring concrete substantially simultaneously on both sides of said sheet.

16. An arch dam comprising an upstream and a downstream arch extending between abutments, the extrados of the downstream arch being substantially in contact with the intrados of the upstream arch, one of said arches being of non-uniform thickness be-⁹⁵tween the crown and the abutments. ¹⁰⁰

17. The method of constructing a concrete arched dam comprising an upstream and a downstream arch with a joint extending up-¹⁰⁵wardly between said arches, there being a sheet of material in said joint, by construct-¹¹⁰ing said dam to a certain elevation, then ex-¹¹⁵tending said sheet upwardly in the direction of said joint, and then placing concrete on both sides of said sheet.

18. In an arched dam comprising a plu-¹²⁰rality of cantilever elements arranged one behind the other in an upstream and down-stream direction, an area of substantially loose contact between at least two adjoining said elements, said area extending from the base of said elements upward to the down-stream face of said dam. ¹²⁵

19. In an arched dam the combination of a plurality of cantilever elements arranged one behind the other in an upstream and down-stream direction, two adjoining said elements being separated by a joint extending substantially from the base of said elements upward to the down-stream face of said dam, and a water-proofing material in said joint.
